UNITED STATES PATENT OFFICE.

BENJAMIN WOLHAUPTER, OF NEW ROCHELLE, NEW YORK, ASSIGNOR TO THE RAIL JOINT COMPANY, OF NEW YORK, N. Y., A CORPORATION OF NEW YORK.

RAIL-JOINT BAR WITH LIGHTENED WEB.

Application filed May 1, 1925. Serial No. 27,249.

To all whom it may concern:

Be it known that I, BENJAMIN WOLHAUPTER, a citizen of the United States, residing at 28 Neptune Ave., New Rochelle, in the county of Westchester and State of New York, have invented certain new and useful Improvements in Rail-Joint Bars with Lightened Webs, of which the following is a specification.

10 This invention relates to rail joints, and particularly to a rail joint bar having a lightened web construction which contains a minimum quantity of metal, and yet possesses adequate strength and stiffness for 15 all practical purposes.

Rail joint bars having subnormally lightened webs have recently been introduced, and found to be susceptible of successful manufacture, as well as capable of sustaining and resisting normal loads. In some forms of these bars, as shown for instance in my former Patent No. 1,482,333 granted January 29, 1924, the subnormal thinned portions of the web extend uninterruptedly 20 from the top to the bottom chords of the bar, thus producing alternate web portions of normal and subnormal thicknesses. These bars are generally rolled into shape and subsequently the bolt holes are formed 25 in the webs. Owing to the manufacturing conditions, these bolt openings may not always register with those portions of the web 30 of normal thickness.

Accordingly, a principal object of the invention resides in providing a lightened web structure for rail joint bars wherein a normal thickness of the web is maintained longitudinally and horizontally thereof in the plane where the bolt holes are to be 35 punched, thereby providing an adequate and substantial thickness of the metal where the bolt holes are located in order that relatively long bolt bearings may be provided for the bolts in the web of the bar, thus obviating or lessening any possible tendency of the 40 bolts to be cut by the light web or the light web to be torn by the bolts. At the same time the improved construction permits of a substantial lightening of the web structure 45 of the bar without impairing its strength and stiffness.

A further object of the invention lies in the provision of a web for rail joint bars which is formed with upper and lower series

of spaced portions of subnormal thickness 55 which form a resultant remaining portion of normal thickness extending centrally and longitudinally of the web throughout its length, and having branches which extend upwardly and downwardly to the top and 60 bottom chords of the bar whereby a minimum quantity of metal will be employed with a maximum amount of strength and stiffness. At the same time this structure produces what may be termed a bolt bearing 65 rib extending longitudinally of the lightened web structure and affording adequate bearings for the bolts.

With the above and other objects in view 70 which will more readily appear as the nature of the invention is better understood, the same consists in the novel construction, combination and arrangement of parts hereinafter more fully described, illustrated and claimed.

Practical embodiments of the invention 75 are shown in the accompanying drawings, in which:

Figure 1 is a perspective view illustrating one form of my invention.

Fig. 2 is a vertical sectional view taken on the line 2—2 of Figure 1.

Fig. 3 is a horizontal sectional view taken on the line 3—3 of Fig. 1.

Fig. 4 is a detailed perspective view of a 80 modification of the invention.

Fig. 5 is a horizontal sectional view taken on the line 5—5 of Fig. 4.

Fig. 6 is a horizontal sectional view showing a further modified form of web.

Fig. 7 is a sectional perspective view illustrating another embodiment of the invention wherein the outside as well as the inside of the web of the bar is altered producing normal and subnormal thickness, and to provide an adequate thickness of the web 90 for the bolt hole positions.

Fig. 8 is a longitudinal sectional view of a portion of the bar shown in Fig. 7, on the line 8—8 of Fig. 7.

Fig. 9 is a sectional perspective view of the invention as applied to the girder type rail joint bar, said view also illustrating lightening the formation of the bar at both the outside and inside of the bar web.

Figs. 10 and 11 are vertical sectional views of the bar shown in Fig. 9 on lines 10—10 and 11—11 of Fig. 9.

Similar reference characters designate corresponding parts throughout the several figures of the drawings.

The present invention aims to produce a rail joint bar of the character set forth in which the web is subnormally lightened in such a manner as to insure the bolt holes being formed in the web and in the plane of normal thickness thereof, in order that relatively long bearings may be provided for the bolts to minimize the tendency of the bolts to be cut by the light webs or the light webs to be torn by the bolts.

To this end, my invention contemplates the provision of a rolled joint bar having a web structure to provide a longitudinally extending portion of normal thickness and in which the bolt holes are formed, and other portions of subnormal thickness which lighten the bar without reducing its necessary strength and stiffness. Although the invention may be carried into effect in connection with joint bars of various types, I have illustrated several forms of the invention in which the joint bar A of substantially I-bar formation is provided with the web portion B which connects the enlarged top compression chord or head C with the enlarged bottom tension chord or foot D. The web portion B, in Figs. 1, 2 and 3, is provided with a portion 1 of normal thickness which extends longitudinally of the bar. This portion 1 is disposed between the top and bottom chords C and D and in line with the bolt holes and can be made of various widths but should be made as narrow as possible to save material and sufficient only to give a proper bearing to the bolts.

The normal thickness of the bar is indicated on the portion 1 in Fig. 1 by the letter X. The inner face of the web, above and below the portion 1 thereof, is formed with a series of upper and lower depressions or sinks 2 and 3 respectively of subnormal thickness, as indicated in Fig. 1 by the reference characters Y and Z. The portions 2 and 3 are produced during the rolling of the bar, usually in the final pass of the rolling mill, and these portions of reduced thickness result not only in the formation of the portion 1 of normal thickness, but also result in the formation of upper and lower branches 4 and 5 from the portion 1, the branches being of normal thickness.

Thus, a longitudinal series of spaced portions 2 of subnormal thickness are disposed above the bolt-hole portion 1, and a longitudinal series of spaced portions 3 of subnormal thickness are disposed below the portion 1. In other words, above and below the longitudinally extending portion 1 there is a series of alternate portions 2 and 4 and 3 and 5 of subnormal and normal thickness respectively. The branches 4 and 5 which are of normal thickness extend upwardly to

the top chord C and downwardly to the bottom chord D. This arrangement produces a novel trussing construction at the inner face of the bar, and provides a longitudinally extending portion intermediate the top and bottom chords for the formation of the bolt openings 6 which are preferably formed by punching. This construction therefore insures the bolt holes always extending through that portion of the thus lightened web which is of normal thickness and thereby providing adequate bolt bearing area for the bolts.

According to the embodiment shown in Figures 4 and 5, the web B may be provided on its inner face with a centrally disposed and longitudinally extending portion 7 of normal thickness, similar to the portion 1 previously described. Bolt holes are formed in this portion 7 of normal thickness. In order to lighten and stiffen the bar, the inner face of the web above and below the portion 7 is formed with a wave-like surface forming alternate portions 9—9 of normal thickness and portions 10—10 of subnormal thickness.

It has now been seen that the fundamental feature of the invention is to provide a lightened structure for the web of a rail joint bar wherein a normal thickness is left throughout the bar longitudinally thereof so that the bolt holes may be punched according to any specification as to the spacing thereof and at the same time providing adequate bearings for the bolts for the purpose hereinbefore explained. This structural feature may be obtained in a bar whose web is deformed at the inside only in order to provide normal and subnormal thickness, as illustrated by the group of Figures 1 to 5 inclusive, but another phase of the invention is exemplified by the group of Figures 6 to 11 inclusive wherein the outside as well as the inside of the web of the bar is deformed to produce the normal and subnormal thicknesses in the web and at the same time provide the bolt bearing rib for the bolt holes, herein referred to. In Figure 6 of the drawings the web B of the bar is shown reduced on both inner and outer faces above and below the longitudinally extending portion 11 of uniform thickness with corrugated portions. Each corrugated portion 12 is of subnormal thickness and forms resultant lightened portions not only on each side of the bar but also above and below the longitudinal portion 11 of uniform thickness.

In Figures 7 and 8 of the drawings a form of the invention is illustrated which is substantially similar to the form shown in Figure 1 of the drawings excepting that the deformations at the inside of the web are duplicated in the outside of the web of the bar. In other words, according to the

- phase of the invention shown in Figures 7 and 8 of the drawings the outside of the web of the bar is deformed to produce the 5 reductions or cavities 2^a which are disposed in staggered relation to the reductions or cavities 2 at the inside of the web. Also the outside deformations leave a normal thickness longitudinally of the bar web as designated by the reference number 1^b 10 lying directly opposite the corresponding element 1 at the inside of the bar, and through this normal thickness 1—1^a of the bar the bolt bearing holes are punched.
- A further exemplification of the invention is shown in Figures 9, 10 and 11 of the drawings wherein the improvements described are shown applied to a girder type of rail joint bar, and in these figures of the drawings similar reference numerals apply to similar corresponding parts shown in Figures 7 and 8 of the drawings. However, in the illustration of Figures 9, 10 and 11 the bolt bearing ribs or thicknesses are duplicated one above the other and said ribs 25 at the inside of the bar are of less width than the diameter of the bolt holes and bolts while the bolt bearing ribs at the outside of the bar are of greater width than the diameter of the bolt holes and the bolts. 30 This construction is necessary in order to give sufficient bearings to permit of the use of bolt heads and washers at the outside of the web of the bar, but as the ribs at the inside of the bar do not form bearings for 35 bolt heads or washers they may be made narrower thus further economizing the saving of metal.
- From the foregoing, it will be seen that the present invention provides a joint bar 40 having a lightened and stiffened web which may be formed by making subnormal portions above and below a longitudinally extending bolt-receiving portion of normal thickness, thus reducing the weight of the 45 bar without materially or proportionately lessening its effective strength, and at the same time insuring the location of the bolt holes in that portion of the bar having a normal thickness, and it will be understood 50 that various changes in the form, proportion and minor details of construction may be resorted to without departing from the spirit of the invention and scope of the appended claims.
- 55 I claim:
1. A rail joint bar including a web member having a portion of normal thickness extending longitudinally thereof, and a portion of subnormal thickness disposed above 60 said portion of normal thickness.
  2. A rail joint bar including a web member having a portion of normal thickness extending longitudinally thereof, and a portion of subnormal thickness disposed below 65 said portion of normal thickness.
  3. A rail joint bar including a web member having a portion of normal thickness extending longitudinally thereof, and portions of subnormal thickness respectively disposed above and below said portion of 70 normal thickness.
  4. A rail joint bar including a web member having a portion of normal thickness extending longitudinally thereof, and a series of spaced portions of subnormal 75 thickness extending in parallelism with said portions of normal thickness.
  5. A rail joint bar including a web member having a portion of normal thickness extending longitudinally throughout the 80 length of the bar, and spaced portions of subnormal thickness disposed above and below said portion of normal thickness.
  6. A rail joint including a web member having a portion of normal thickness extending longitudinally thereof, and a portion of subnormal thickness disposed above 85 said portion of normal thickness, said web being formed with a plurality of bolt openings extending through the web portion of 90 normal thickness.
  7. A rail joint bar including a web member having a portion of normal thickness extending longitudinally thereof, and a portion of subnormal thickness disposed below 95 said portion of normal thickness, said web being formed with a plurality of bolt openings extending through the web portion of normal thickness.
  8. A rail joint bar including a web member having a portion of normal thickness extending longitudinally thereof, and spaced portions of subnormal thickness respectively disposed above and below said portion of 100 normal thickness, said web being formed 105 with a plurality of bolt openings extending through the web portion of normal thickness.
  9. A rail joint bar including a web member having a portion of normal thickness extending longitudinally thereof, and a series of spaced portions of subnormal thickness extending in parallelism with said portions of normal thickness.
  10. A rail joint bar including top and bottom compression and tension chords respectively and a web member connecting said chords, said web member being provided with a longitudinally extending portion of normal thickness and with a plurality of 115 spaced portions of subnormal thickness.
  11. A rail joint bar including top and bottom compression and tension chords respectively and a web member connecting said chords, said web member being provided with a series of spaced portions of subnormal thickness forming a resultant remaining portion of normal thickness extending centrally and longitudinally of the web 120 throughout its length and having branches 125
  - 130

extending upwardly and downwardly to the top and bottom chords.

12. A rail joint bar including top and bottom compression and tension chords respectively and a web member connecting said chords, said web member being provided with upper and lower series of spaced portions of subnormal thickness forming a resultant remaining portion of normal thickness extending centrally and longitudinally of the web throughout its length and having branches extending upwardly and downwardly to the top and bottom chords, said web being provided with a plurality of bolt openings in register with said longitudinally extending portion of normal thickness.

13. A rail joint bar including a web member having its outer and inner sides deformed producing normal and subnormal thicknesses and a longitudinally extending bolt bearing rib.

14. A rail joint bar including a web member having the outer and inner sides thereof deformed producing normal and subnormal thickness, a part of the normal thickness of the web extending longitudinally thereof in the plane of the bolt hole positions.

15. A rail joint bar including a web mem-

ber having a portion of normal thickness extending longitudinally thereof, and spaced 30 portions of subnormal thickness respectively disposed above and below said portion of normal thickness.

16. A rail joint including enlarged top and bottom compression and tension chords 35 respectively and a web member connecting said chords, said web member being provided with a longitudinally extending portion of normal thickness and with a plurality of spaced portions of subnormal thick- 40 ness.

17. A rail joint bar including enlarged top and bottom compression and tension chords respectively and a web member connecting said chords, said web member being 45 provided with upper and lower series of spaced portions of subnormal thickness forming a resultant remaining portion of normal thickness extending centrally and longitudinally of the web throughout its 50 length and having branches extending upwardly and downwardly to the top and bottom chords.

In testimony whereof I hereunto affix my signature.

BENJAMIN WOLHAUPTER.
